UNITED STATES PATENT OFFICE.

WILLIAM RICHEY, OF CHICOOEE FALLS, MASSACHUSETTS, ASSIGNOR TO A. G. SPALDING & BROS., OF JERSEY CITY, NEW JERSEY, A CORPORATION OF NEW JERSEY.

TENNIS-RACKET.

1,333,876.

Specification of Letters Patent. Patented Mar. 16, 1920.

Application filed April 7, 1919. Serial No. 288,142.

To all whom it may concern:

Be it known that I, WILLIAM RICHEY, a citizen of the United States, and resident of Chicopee Falls, Massachusetts, have invented certain new and useful Improvements in Tennis-Rackets, of which the following is a specification.

My invention relates to tennis rackets having a reinforcement at the throat piece, where weakness would exist were a reinforcement not employed, owing to the fact that the gluing surface of the throat piece at the upper portion thereof where it joins the arms of the bow is largely end grain.

Reinforcing means has been proposed heretofore in which the grain thereof runs at right-angles to the grain of the throat piece and in carrying out my invention I employ a reinforcing member or members of this sort.

One object of my invention is to provide a construction that may be made with few operations and which will facilitate rapidity of assembly, enabling quantity production to be secured at a minimum expense and with uniform accuracy. I aim to preserve to maximum extent the strength of the arms of the bow and at the same time present a large area of contact between the reinforcing member or members and the said arms, the reinforcing means reaching approximately along the entire end grain portion of the throat piece or along a considerable extent of said portion.

In the accompanying drawings;

Figure 1 is a side view of the portion of the racket where the throat piece is located.

Fig. 2 is a sectional view of a portion of the throat piece.

Fig. 3 is a modification, the view being similar to that of Fig. 1.

Fig. 4 is a view of a modification in which the recesses in the arms of the bow are cut deeper than in the other forms.

In carrying out the invention the racket frame may be presented to a rotary cutter, the axis of which is at the point *x*, so that the cutter will form recesses in the side arms of the bow on the line *y*—*y*. The cutter produces a narrow recess, such as to receive a thin reinforcing piece or pieces indicated at 1 in Fig. 2, which represents the upper portion of the throat piece in vertical section. After the recesses are formed the

throat piece may be inserted between the arms of the bow, this throat piece having previously been built up with the reinforcing member, or members, 1 glued therein and having portions thereof projecting as at 2, so as to enter and fill the recesses defined by the lines *y*. The recesses in both of the arms of the bows may be formed at one operation and where a built-up throat piece A is employed this is inserted between the arms of the bow by moving it in a direction from the head of the bow toward the lower end of the handle, and in this assembling movement the projecting portions 2 of the reinforcing member, or members, will enter the recesses defined by the lines *y* and glue having been applied the parts are united.

Instead of proceeding as above the throat piece first may be inserted and glued in place between the arms of the bow and then by presenting the racket frame to a circular cutter the necessary slits will be formed in the throat piece and also in the arms of the bow at one cutting operation, after which the reinforcing members which have been formed to fit in these slits and recesses may be inserted in place properly supplied with glue and the parts will thus be united together.

In the construction shown in Fig. 1 in order to get a sufficient depth of the recesses in the arms, for instance as defined by the lines *y*—*y* the cutter will be located as above stated at the point *x* and therefore the recesses in the arms of the bow will extend above the upper surface of the throat piece and the reinforcing members will be provided with ends as at 3 to fill these extensions of the recesses.

If it is desired however to have the ends of the reinforcing pieces terminate at the corners where the top of the throat piece joins the side arms the recesses in the arms may be formed on the lines *y*'—*y*' of Fig. 3 and these may be produced with a single cutter which will operate on the side arms of the bow previous to the insertion of the throat piece. The throat piece may be formed with the slits to receive the reinforcing pieces by presenting it to a saw or saws which will cut the slits down to the straight transverse line or bottom *y* and the reinforcing pieces will be shaped to fill these slits having for this purpose straight

edges at the points y^2 and the segmental projections at $2'$. In both forms, however, the recesses defined by the lines $y-y$ or $y'-y'$ will be of sufficient length to provide projecting portions of the reinforcing members which will extend a material distance along the end grain sides at 4 of the throat piece, so that in large measure these end grain portions of the throat piece will 10 be reinforced by the segmental projecting portions of the inserted members and at the same time the side arms will have a material portion of their body left uncut at the points z , from all of which it will be seen 15 that while the end grain parts of the throat piece are reinforced the side arms are left of material strength.

It will be noticed that the reinforcing effect of the projecting segmental portions 20 will extend from the top of the yoke down to the points 5.

In both forms the edges of the segmental ends of the reinforcing piece will find a bottom, namely, the curved wall of the recess 25 to bear against with some of the glue interposed and this will be so throughout the extent of the edge of the segmental projections and thus these portions will become substantially integral with the continuous 30 intact portions of the arms at z .

As above pointed out the manufacture can be carried on rapidly owing to the fact that one cutting action makes the recesses in both arms.

It will be observed that the insert or reinforcing members have their grain running transverse to the longitudinal axis of the racket, and the edges of these inserts where they lie at the bottoms of the recesses and 40 against the material of the arms of the bow present end grain surfaces which are tied or united to the bottom walls of the recesses by the glue making a firm connection at these points in addition to the function of 45 the insert pieces acting as reinforcing

means for the end grain surfaces of the throat piece.

I do not limit myself to the material of which the insert member is composed.

In Fig. 4 I show the recesses cut deeper 50 into the bow arms by allowing the circular cutter to pass to a point where its axis will be below the plane of the upper ends or mouths of the recesses. These recesses therefore will have short straight portions 55 at their upper ends tangent to the arc-shaped portions.

What I claim is:

1. A tennis racket, having arc shaped recesses in the inner sides of its arms each 60 struck from a point between the arms and leaving the outer portions of the arms intact and a throat piece having a reinforcing member inserted therein and having segmental projecting portions to fit the said recesses, said throat piece with its reinforcing member being glued in place, substantially as described.

2. A tennis racket having recesses in the inner sides of the arms of its bow, each 70 struck from a point between the arms, the bottoms of which recesses form arcs of the same circle, and a throat piece having reinforcing members inserted therein with segmental projecting portions fitting in the 75 arc shaped recesses of the arms of the bow and glued in place, substantially as described.

3. A tennis racket having arc shaped recesses in its arms, each struck from a point 80 between the arms and a throat piece having an insert member or members with the grain running substantially at right-angles to the axis of the racket and with arc-shaped edges presenting end grain surfaces 85 to the bottom walls of the recesses and united thereto by glue, substantially as described.

In testimony whereof I affix my signature.
WILLIAM RICHEY.
